DESIGN FOR AN ELECTRIC SIGN BASE

Joseph M. Mattias, West Warwick, R. I.

Application June 14, 1938, Serial No. 77,838

Term of patent 3½ years

To all whom it may concern:

Be it known that I, Joseph M. Mattias, a citizen of the United States, residing at West Warwick, in the county of Kent and State of Rhode Island, have invented a new, original, and ornamental Design for an Electric Sign Base, of which the following is a specification, reference being had to the accompanying drawing, forming part thereof.

Figure 1 is a front elevational view of the electric sign base, showing my new design.

Figure 2 is a plan view thereof.

Figure 3 is an end elevational view of the sign base.

I claim:

The ornamental design for an electric sign base, as shown.

JOSEPH M. MATTIAS.
